INTERNAL-COMBUSTION ENGINE

William H. Cords, San Diego, Calif.

Application October 11, 1943, Serial No. 505,787

4 Claims. (Cl. 121—1)

This invention relates to internal combustion engines and relates particularly to improvements relative to the connections between the crank-shaft pitman and piston of the engine.

It is the general object of the present invention to provide an internal combustion engine with means for developing a greater torque during the initial portion of the combustion cycle of the engine. As the internal combustion engines are now designed, the explosive charge is ordinarily fired at or close to the moment that the pitman holds the piston at dead center position with relation to the crank-shaft. As a result, in the first portion of the combustion cycle very little torque is developed by the engine.

In the present invention, I employ a piston which is provided with two relatively movable parts, one part being pivoted relative to the other part, and I provide a crank arm connection between this pivoted portion and the pitman of the engine, which is designed to permit the explosion at the dead center position of the pitman to apply a torque for rotating the crank-shaft. By this new arrangement of parts, I have greatly increased the torque of the engine and improved considerably its performance.

The present invention will best be understood from the following description of the preferred form or forms of engines embodying the present invention, as described in connection with the accompanying drawings, in which

Figure 1 is a fragmentary vertical section on the line 1—1 of Figure 2.

Figure 2 is a horizontal section on the line 2—2 of Figure 1.

Figure 3 is a similar horizontal section, showing the invention used in connection with the cylinder of modified shape.

Figure 4 is an elevation in section, showing the manner of converting a conventional engine to incorporate the present invention.

Figure 5 is an inverted view of the piston of Figure 4.

Figure 6 is a section taken along the line 6—6 of Figure 4.

Figure 7 is a section on the line 7—7 of Figure 4.

Referring to the drawings, in Figures 1 and 2, 2 indicates cylinder walls which in cross-section, as viewed in Figure 2, may be somewhat egg-shaped so as to place the larger area of the piston (hereinafter described) to one side of the pivot point of the pitman. However, an alternate form for the cylinder cross-section may be that indicated by 2a in Figure 3.

Within the cylinder there is provided a piston including two pivotally connected parts 3 and 4, 4 being the upper piston member and 3 being the lower piston member. These members are pivoted together, as indicated at 5, at a point near the smaller end of the cylinder. The lower piston member 3 is provided with a sleeve 6 to which are journaled pins 7 of the pitman or connecting rod 8. This pitman or connecting rod 8 is connected in the usual manner with the crank 9 of the crank-shaft 10. The crank-shaft 10 is located in alignment with the axis of the pins 7 and, therefore, to one side of the center of the cylinder 2. The connecting rod 8 is provided with an arm 11 extending at substantially right angles to the body of the rod 8 and formed rigidly with the rod 8.

The arm 11 extends to nearly the opposite side of the piston from the side to which the sleeve 6 is connected, and there the arm 11 is pivotally connected to the link 12, which is in turn pivotally connected to the top piston member 4. Rings 13 are provided with a top piston member and one or more rings 14 may also be provided with a bottom piston member, which may have an elongated skirt 15 extending downward beneath the link 12.

In Figure 1 the engine is shown in its intended position just at or substantially at the initiation of the combustion cycle of the engine. The connecting rod 8 is on the dead center position between the crank-shaft 10 and its pivot pins 7 connecting it with the lower piston member 3. In this position, however, because of the lateral arm 11 connected to the connecting rod and its connection in turn with the upper piston member 4, the combustion of the charge within the cylinder is capable of providing substantial torque tending to rotate the crank 9 about the crank-shaft. At the instigation of combustion the upper piston member 4 pivots relative to the lower piston member 3 in a turning movement developed by the arm 11 on the connecting rod 8, which in turn provides a torque acting to rotate the crank-shaft.

Now, referring to Figures 4 to 7, inclusive, I have shown a modification of the invention designed to enable the ordinary engines of commerce to be converted to incorporate the principles of the present invention. In said figures, 20 indicates any ordinary cylinder, 21 the crank-shaft of the engine which is in this case indicated as in alignment with the center of the piston 20. A crank 22 is provided as connected by a connecting rod 23 pivoted at 24 to the lower end of the

piston member 25. An upper piston member 26 is provided which is pivoted as indicated at 27 to the lower piston member near one side of the cylinder 20. Rings 28 and 29 may be provided with upper and lower piston members.

The connecting rod 23 is provided with an integral laterally extending arm 30, which is pivotally connected to the link 31, which in turn is pivotally connected at 32 to upper piston 26. The engine shown in Figures 4 to 7 operates in a manner similar to that of Figures 1 and 2. The arm 30 and its link connection 31 with the upper piston member 26 enables the development of a turning movement on a connecting rod 23 at the start of the combustion cycle. This turning movement applied to the arm 30 is in turn effective for applying a torque for rotating the crank-shaft 21.

While the particular engines herein described have proven capable in practice of accomplishing the objects of the present invention, it is to be understood that the invention is capable of modification and change, and this invention includes such modification and change as come within the scope of the appended claims.

I claim:

1. In an engine, the combination with a cylinder and crank-shaft of an upper and a lower piston member movable in said cylinder, the upper piston member being pivotally mounted on the lower piston member and a connecting rod connected to said crank-shaft and pivotally to said lower pivot member, said connecting rod having a laterally extending arm connected to said upper piston member.

2. In an engine, the combination with a cylinder

and crank-shaft of an upper and a lower piston member movable in said cylinder, the upper piston member carrying piston rings and being pivoted to the lower piston member near the cylinder walls, a connecting rod connected to the crank-shaft and pivotally to the lower piston member, said connecting rod having a laterally extending arm linked to the upper piston member.

3. An engine, comprising a combination with a crank-shaft and a cylinder, the cross-section of said cylinder having an enlarged side and a reduced side, the crank-shaft being displaced from the center of the cylinder towards the reduced side, of an upper and lower piston member for said cylinder, the upper piston member being pivotally mounted on the lower piston member near the reduced side and a connecting rod from said crank-shaft pivotally connected to said lower piston member, said connecting rod having a laterally extending arm linked to said upper piston member.

4. An engine in which means are provided for applying torque between the piston and crank-shaft in the dead-center position of said crank-shaft, said engine including a cylinder and crank-shaft, a lower piston member movable in said cylinder and pivotally supporting an upper piston member, a connecting rod between said crank-shaft and lower piston member pivotally connected to said lower piston member, said connecting rod having a laterally extending arm and a link pivoted to said arm at one end and to said upper piston member at the other end.

WILLIAM H. CORDS.
